UNITED STATES PATENT OFFICE

SAMUEL MARKEL, OF PIPESTONE, MINNESOTA.

MOLD FOR CONSTRUCTING HOLLOW REINFORCED-CONCRETE WALLS.

1,123,563.

Specification of Letters Patent.

Patented Jan. 5, 1915.

Application filed August 9, 1911. Serial No. 843,159.

To all whom it may concern:

Be it known that I, SAMUEL MARKEL, a citizen of the United States, residing at Pipestone, in the county of Pipestone and State of Minnesota, have invented a new and useful Mold for Constructing Hollow Reinforced-Concrete Walls, of which the following is a specification.

The invention relates to improvements in molds for making hollow reinforced concrete walls.

The object of the present invention is to improve the construction of molds for making various kinds of concrete walls, reinforced or otherwise, and adapted to enable a fire-proof, frost-proof and water-proof wall of this character to be easily and quickly constructed at a minimum cost.

A further object of the invention is to provide a mold of this character, capable of molding two successive courses of a wall in each of its positions on the same.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:—Figure 1 is a perspective view of a mold, constructed in accordance with this invention and shown applied to a wall. Fig. 2 is a plan view of the same partly in section. Fig. 3 is a vertical sectional view of the same, the parts being arranged for making the upper course. Fig. 4 is a similar view, the parts being arranged for constructing the lower course.

Like numerals of reference designate corresponding parts in all the figures of the drawings.

In the accompanying drawings in which is illustrated the preferred embodiment of the invention, 1 designates vertical standards or posts transversely alined and arranged at suitable intervals and spaced apart by upper and lower transverse gage bars 2 and 3, which are of a length to space the posts or standards a distance equal to the thickness of the wall and a thickness of side planking 4, arranged at the inner faces of the posts or standards and supported in

position by the same and constituting the side walls of the mold. The side planking is preferably two feet in width and is adjustable from the lower to the upper portion 60 of the frame-work of the mold for enabling two courses of approximately two feet to be successively molded or constructed before changing the position of the mold on the wall. The posts or standards are connected 65 at each side of the mold to form the frame-work thereof by means of inclined longitudinally disposed braces 5, preferably consisting of rods provided at their ends with eyes or openings 6, and secured to the standards or posts by upper and lower transverse connecting rods 7 and 8, which pierce the standards or posts and hold the same against outward movement and maintain the said standards or posts in proper contact with the 70 transverse gage bars, whereby the proper thickness of the wall is maintained and the frame-work secured in plumb position. Although the braces are shown in the form of the inclined rods 5, the braces may be 75 constructed of wood, or other suitable material and may be arranged in any other preferred manner to secure the requisite strength of the frame-work of the mold. The frame-work may also be braced at the 80 corners or angles by means of straight horizontal rods 9, which connect the adjacent standards or posts at the outer side of the mold. The transverse rods 7 and 8 have threaded terminals and are provided with 85 nuts 10, which engage either the standards or posts at the terminals of the braces.

The standards or posts are provided at their upper ends with transversely alined recesses 11, and the upper gage bars 2 are 90 provided at their ends with lower recesses 12, forming terminal projections 13 to fit in the recesses 11 of the upper ends of the standards or posts and providing shoulders 14, which engage the standards or posts at 95 the inner faces thereof to limit the inward movement of the same, whereby the standards or posts are properly spaced at the top. The upper gage bars are also provided at their lower edges with central, longitudinally alined recesses 15 for the reception of a longitudinal connecting bar 16 of cores 17, when the apparatus is arranged for molding the upper course, as illustrated in Fig. 3 of the accompanying drawings.

The standards or posts are equipped at a point intermediate of their ends with ap-

proximately L-shaped brackets 18, designed to be constructed of metal or other suitable material consisting of a lower or base portion, and an upwardly projecting portion spaced from the standards or posts and forming a recess 19 to receive the lower transverse gage bar 3. The supporting brackets 18 are arranged in transverse alignment at the side faces of the posts or standards, and the lower transverse gage bars are provided with terminal recesses 20, located at the lower edges of the gage bars and forming spaced projections 21 and inner shoulders 22. The upper projections fit in the recesses 19 of the supporting brackets, and the shoulders 22 abut against the inner side edges or faces of the brackets and limit the inward movement of the standards or posts and maintain the latter in proper spaced relation to provide a wall of the proper thickness and to form annular spaces for the side planking. The lower transverse gage bars are also provided in their upper edges with central longitudinally aligned recesses 23 for the reception of the longitudinal connecting bar 16 of the cores 17. In molding the lower one of the two courses to be made by the mold, the longitudinal bar 16, which connects the cores, is arranged in the centrally aligned recesses 23 and is supported by the gage bars 3. The cores 17, which depend from the longitudinal connecting bar 16, are alternately secured at their upper ends to the opposite side faces of the same by means of transverse bolts 24, which pierce the cores and the connecting bar 16. The cores are arranged in spaced overlapping relation, and are adapted to form two longitudinal series of vertical air spaces 25 in the wall 26, the vertical air spaces extending from the top to the bottom of the wall, and the air spaces of one series being arranged opposite the intervals between the air spaces of the other series, and extending beyond the planes of the end walls of such air spaces, as clearly shown in Fig. 2 of the drawings. By this arrangement the entire length of the wall is interrupted by air spaces and is thereby rendered frost-proof. The cores have a slight downward taper from their upper to their lower ends to enable them to be readily introduced into the air spaces of the wall previously made, and to permit them to be easily withdrawn from the concrete after the same has set.

In starting the work upon the foundation, the mold is set up on the foundation and is made plumb by fastening the structure together, a corner being always used. The top of the foundation must be level, or the frame-work must be leveled up. The standards or posts after being set up on a level surface are made plumb by the use of the upper and lower transverse gage bars, which accurately space the standards or posts at the top and center the exact distance required to mold the wall and to provide the necessary space for the side planking or side walls of the mold, and the said standards or posts are firmly held in such position by tightening the upper and lower horizontal transverse rods. The planking is then placed on the inside of the framework against the inner faces of the standards or posts and the mold is then ready to begin work. After the first course has been molded, the apparatus is mounted upon the same in the following manner: The standards or posts are placed over the wall and are let down until the lower horizontal transverse rods 8 rest upon the top of the wall. The lower ends of the standards or posts are spaced from the sides of the wall the proper distance by means of blocks 27, which are detachably secured by screws 28, or other suitable fastening devices to the inner faces of the standards or posts below the lower transverse rods 8, as clearly illustrated in Figs. 3 and 4 of the drawings. The lower ends of the standards or posts may be beveled, as shown, or cut square. The upper and lower transverse gage bars are then placed in position and the transverse rods tightened to hold the framework firmly in position. The side planking or walls are then placed in position and the work is continued. In molding the lower one of the two courses made in each position of the apparatus, the longitudinal connecting bar is placed in the upper recesses 23 of the lower gage bars 3 and are supported by the latter, as clearly illustrated in Fig. 4 of the drawings. After the first course has been set, the side planking or walls are raised to the upper portion of the framework for molding the second course, being supported in position by the wall, or a second set of planking or wall sections may be placed upon the side planking previously used. The cores are then elevated, the longitudinal core connecting bar being supported upon the upper transverse rods 7 and being held in proper position centrally of the wall by the lower central recesses 15 of the upper gage bars 2, as clearly illustrated in Fig. 3 of the drawings.

The concrete wall may be reinforced by vertical rods 29, horizontal connecting wires 30 and transverse reinforcing members 31. The rods 29 are arranged in a vertical position at suitable intervals, and the connecting wires 30 are arranged horizontally at regular intervals and are suitably connected to the rods. The transverse reinforcing members 31 are arranged horizontally and have angularly bent terminals extending in opposite directions. These transverse reinforcing members may be arranged either in straight transverse lines at right angles

to the planes of the side faces of the walls, as illustrated in Fig. 1 of the drawings, or they may be disposed diagonally, as shown in Fig. 2. Any other reinforcing material 5 may, however, be embedded in the concrete. When desired, the wall may be water-proof by putting on the outside a coating of about a quarter of an inch in thickness of cement mixed with sand in the proportion of two 10 of sand to one of cement. The coating may be left smooth, or may be made to represent brick or stone and coloring matter may be used to give the desired effect.

Having thus fully described my invention, 15 what I claim as new and desire to secure by Letters Patent, is:—

1. A mold of the class described comprising a framework including spaced standards arranged in pairs, transverse rods connecting the standards and having adjusting means for moving the standards inwardly, and gage bars extending across the mold and engaging and spacing the standards at a point above the said rods, a bar extending 20 longitudinally of the mold between the standards thereof and engaged by the gage bars and supported by the said transverse rods, and a series of cores connected with and supported by the said bar.

2. A mold of the class described comprising a framework including spaced standards arranged in pairs, lower transverse rods connecting the standards and having adjusting means for moving the standards inwardly to clamp them against a wall, gage bars extending across the mold and engaging and spacing the upper ends of the standards and upper transverse rods located beneath the gage bars and connecting the 35 standards, a bar extending longitudinally of

the mold between the standards thereof and engaged by the gage bars and supported by the upper transverse bars, and a series of cores connected with and supported by the said bar. 45

3. A mold of the class described including standards arranged in pairs, transversely aligned brackets carried by the standards and located at points intermediate of their ends, gage bars having terminal recesses to fit 50 the brackets, means for adjustably connecting the standards to clamp the same against a wall, and a core having a longitudinal bar supported by the said gage bars.

4. A mold of the class described comprising a framework including standards arranged in pairs and provided at their upper ends with transversely aligned recesses, transversely aligned brackets carried by the standards and located at points intermediate of 60 their ends, gage bars having terminal recesses to fit the brackets and the upper recesses of the standards and means located below the gage bars for adjustably connecting the standards to clamp the same against 65 a wall, whereby the framework is adjustably mounted thereon, side walls arranged at the inner faces of the standards, and a core having a longitudinal supporting bar adapted to engage with the said gage bars 70 and shiftable from the lower to the upper portion of the mold.

In testimony, that I claim the foregoing as my own, I have hereto affixed my signature in the presence of two witnesses.

SAMUEL MARKEL.
